HEM-FOLDING AND SHAPING DEVICE FOR
SEWING MACHINESJames E. Ackerman, Devon, Conn., assignor to
The Singer Manufacturing Company, Eliza-
beth, N. J., a corporation of New Jersey

Application March 2, 1935, Serial No. 9,010

6 Claims. (Cl. 112—141)

This invention relates to improvements in work-folding and guiding devices for sewing machines and has for its object to provide means for producing a hem of uniform width in a body material, and particularly in body materials having heavy cross-seams.

The invention consists in the work-folding, guiding and feeding devices as hereinafter described and pointed out in the appended claims.

In the accompanying drawings, Fig. 1 is a front side elevation, partly in vertical section, of a portion of a sewing machine having the present improvements applied thereto. Fig. 2 is a front end elevation of the sewing machine, with the cloth-plate partly in section. Fig. 3 is a top plan view of a portion of the cloth-plate of the sewing machine and of the attachment applied thereto, the presser- and feed-bars being shown in horizontal section. Fig. 4 represents a perspective view of the shaping member for the inner fold-edge of the hem. Fig. 5 represents a sectional view of the hem-shaping elements, taken substantially on the line 5—5 of Fig. 3. Fig. 6 represents a section similar to Fig. 5, but taken on the line 6—6 of Fig. 3. Fig. 7 represents a perspective view of the hemmer.

Referring to the drawings, a commercially well known sewing machine, to which the present improvements have been applied, has a frame including a bed-plate 1 and a hollow bracket-arm 2 terminating in a head 3 overhanging the bed-plate, said bed-plate serving as a work-support or cloth-plate.

Rotatably journaled in suitable bearings in the bracket-arm 2 is a main or needle-reciprocating shaft 4 operatively connected by a link 5 to a vertically reciprocating needle-bar 6, carrying at its lower end a needle 7. The needle-bar 6 is journaled for endwise reciprocation in suitable bearings provided in a vibratory frame 8 hung upon a fulcrum-pin 9 for vibratory work-feeding movements about an axis substantially parallel to the axis of rotation of the main shaft 4. The needle-bar frame 8 derives its vibratory movements from a crank-arm 10 of a rock-shaft 11 journaled in the bracket-arm 2 below and in parallel relation with the main shaft 5, said rock-shaft 11 being actuated in the usual or any suitable manner.

Suitably secured upon the bed-plate 1 is a throat-plate 12 having a feed-slot 13 through which operates a lower feed-dog 14 having a needle-aperture 15, said feed-dog being actuated in the usual or any suitable manner to advance

the work in timed relation with the work-feeding movements of the laterally vibrated needle 7.

Opposed to the lower feed-dog 14 is an upper feeding foot 16, preferably having a serrated work-engaging face and provided with a needle-aperture 17. The shank of the feeding foot 16 is secured upon the lower end of a feed-bar 18 journaled for vertically reciprocatory movements in a suitable bearing aperture provided in the vibratory frame 8. The upper end of the feed-bar 18 is connected by a link 19 to one arm of a horizontally disposed rock-lever 20 pivotally mounted intermediate its ends upon a fulcrum-block 21 suitably secured upon a vertically disposed presser-bar 22. The other arm of the 10 rock-lever 20 is connected by a bent link 23 to a crank-arm 24 of a rock-shaft 25 journaled in bearing brackets at the rearward side of the bracket-arm 2. The rock-shaft 25 carries another crank-arm 26 connected to one end of a pitman 27, of which the opposite end has a strap 20 embracing an eccentric 28 upon the main shaft 4. Upward movement of the feed-bar 18 under the action of the rock-lever 20, is yieldingly opposed by a spring 29, as more fully disclosed in the prior U. S. patent of M. L. Waterman, No. 1,916,180, June 27, 1933.

The presser-bar 22 is mounted for vertical movement in bearing bushings 30 and 31 provided in the bracket-arm head 3, and is yieldingly depressed by a spring 32 in the usual manner. Secured upon the lower end of the presser-bar 22 is the shank 34 of a presser-foot 35 having its tread portion cut away at one side to provide clearance for the feeding foot 16. 35 The presser-foot 35 has an upturned toe portion 35' and a serrated work-engaging face having its heel terminating closely adjacent to a plane transverse to the line of feed and containing the needle at its limit of rearward or feeding movement. It will be understood from the foregoing description that the presser-foot 35 is vertically reciprocated to engage and release the work during each stitch-forming cycle and that the work is advanced by the feeding means while the presser-foot is raised above and clear of the work. The termination of the heel of the presser-foot closely adjacent to the needle-path, as above described, enables the presser-foot to step off from heavy cross-seams or other bulky 40 ridges and to engage the relatively thinner portion of the work at the proper time to efficiently hold the work upon the work support between successive penetrations of the work by the needle. 45

Pivotedly mounted upon the bed-plate 1 is the 55

usual attachment holder 36, upon which the base-plate 37 of the primary hem-forming guide or hemmer is secured, by screws 38, for adjustment of the hemmer crosswise of the line of seam formation. The base-plate 37 has an upstanding flange 39 to which is soldered or otherwise suitably secured a diminishing spiral hem-forming scroll, comprising an apron 40 merging into an upturned concave guiding wall 41 for initially forming the outer fold edge of a hem, said wall 41 continuing into a roof-portion 42 curving downwardly and inwardly as an inner fold-edge forming lip 43 extended axially of the scroll beyond said wall 41.

Opposed to the inner fold-edge forming portion or lip 43 of the scroll, at the delivery-end of the hemmer, is an auxiliary upturned concave wall 44 for guiding the outer fold-edge of the hem, said auxiliary wall 44 being laterally yieldable to provide the necessary clearance when bulky ridges occur in the work passed through the hemmer. The auxiliary wall 44 is carried by one arm of an angle-lever 46 fulcrumed upon the base-plate 37 for horizontal swinging movements, by means of a pivot-screw 47. Connected to the other arm of said lever 46 is a spring 48 anchored to the base-plate to bias the wall 44 laterally into yielding engagement with the wall 41 to constitute a continuation of the delivery end of the latter. The base-plate 37 has an angular flange constituting a guide for directing the outer fold-edge of the formed hem, said flange presenting a guiding face 49 inclined to the line of seam formation and merging into a guiding face 50 substantially parallel to the line of seam formation. The guiding face 49 is inclined in a direction to deflect the outer fold-edge of the formed hem into the plane of the face 50 and more particularly when the auxiliary wall 44 of the hemmer has been moved laterally by the work from normal position. The flange-face 50 is disposed adjacent to the presser-foot toe 35', said face 50 being preferably spaced a greater distance from the line of seam formation than the outer fold-edge guiding wall 41 of the hemmer.

The hemmer described serves to somewhat loosely roll the margin of a body material in the form of a complete hem, which becomes flattened as it passes under the presser-foot toe 35'. This flattening of the hem roll tends to widen the hem and it is to accommodate this effect that the guiding face 50 is spaced a greater distance from the seam line than the hemmer wall 41. However, the laterally yielding movements of the wall 44 of the hemmer and also the hem-flattening action of the presser-foot make uncertain the final width of the hem to be secured by the stitches. To insure that the hem presented to the needle is of constant width, hem-shaping means is provided to act upon the hem between the delivery end of the hemmer and the needle.

To this end, a bracket 51 is suitably clamped upon the lower presser-bar bushing 31 and depends therefrom adjacent to the shank of the presser-foot. Fulcrumed between its ends upon said bracket 51, by means of a pivot-bolt 52, is the carrier 53 of a hem-fold shaping member 54, a spring 55 being connected to the rearward arm of the carrier 53 and anchored to the bracket 51 to yieldingly urge the shaping member toward the work-support. The shaping member 54 has a vertically disposed edge-guiding face 54' extending substantially parallel to the line of seam formation and closely adjacent to the presser-

foot 35, said shaping member being disposed at the side of the presser-foot opposite to the edge-guide flange 49, 53. The toe 56 of the shaping member is bent laterally away from the seam line and extends forwardly to a point adjacent the hemmer lip 43, whereby the delivery end of the hemmer is disposed between the shaping member and the edge-guide flange 49. Extending laterally from the lower edge of the shaping-member 54 and underneath the presser-foot toe 35' is a fin 57, of which the portion adjacent the toe 56 merges into a concave guiding face 58 of the shaping member, which guiding face is rearwardly inclined toward the line of seam formation. At its rearward end, the fin 57 is substantially normal to the face 54' of the shaping member.

As the hem rolled by the hemmer passes under the presser-foot toe 35' and is gradually flattened thereby, the inclined concave face 58 of the shaping member 54 acts upon the inner fold-edge of the hem to crowd the inturned margin of the body material toward the outer fold-edge of the hem. The hem thus reshaped as it is flattened has its inner and outer fold-edges definitely located by the shaping member 54 and the opposed flange 50, undue thicknesses in the hem due to cross-seams and the like being accommodated by the vertically yielding movements of the presser-foot. Consequently, the width of the hem progressively presented to the needle is substantially constant.

Having thus set forth the nature of the invention, what I claim herein is:—

1. In a sewing machine, stitch-forming mechanism including a reciprocatory needle, work-feeding means, a presser-foot, a hem-folder disposed in front of said needle having means for folding a margin of body material back upon itself to form the outer fold of a hem, and for inturning the edge of the folded back margin to thereby form the inner fold of the hem, a hem-shaping member having a vertically concave guiding face inclined rearwardly toward the line of seam formation and disposed for engagement in advance of said needle by said inner fold of the hem delivered by said hem-folder, said concave guiding face terminating at its lower edge in a fin extending underneath said presser-foot, and an outer hem-fold edge-guide opposed to said guiding face.

2. In a sewing machine, stitch-forming mechanism including a reciprocatory needle, work-feeding means, a presser-foot, a folder disposed in front of said needle having means for folding a margin of body material back upon itself and for inturning the edge of said margin to thereby form a hem-fold, hem-shaping means disposed between said folder and the needle comprising guiding walls arranged to narrow to a predetermined width the hem-fold delivered by said folder, and means for reciprocating said presser-foot relatively to said hem-shaping means to engage and release the work during each stitch-forming cycle.

3. In a sewing machine, stitch-forming mechanism including a reciprocatory needle, work-feeding means, a presser-foot, a hem-folder disposed in front of said needle having means for folding a margin of body material back upon itself to form the outer fold of a hem, and for inturning the edge of the folded back margin to thereby form the inner fold of the hem, opposed guiding walls for directing the inner and outer

fold-edges of said hem between the delivery end 5 of said hem-folder and said needle, the inner fold-edge guide being rearwardly inclined toward the line of seam-formation to thereby crowd the inner fold of the hem toward the outer fold thereof, and means for reciprocating said presser-foot relatively to said guiding walls to engage and release the work during each stitch-forming cycle.

4. In a sewing machine, stitch-forming mechanism including a reciprocatory needle, work-feeding means, a presser-foot, a folder having means for folding a margin of body material back upon itself and for inturning the edge of 10 said margin to thereby form a hem-fold, guides disposed at opposite sides of said presser-foot between the delivery end of said folder and said 15 needle for directing the inner and outer fold-edges of said hem, the inner fold-edge guide having a fin extending underneath said presser-foot, and means for reciprocating said presser-foot relatively to said guides to engage and release the work during each stitch-forming cycle.

5. In a sewing machine, a work-support, stitch-forming mechanism including a reciprocatory needle, work-feeding means, a presser-foot, a folder disposed in front of said presser-foot having means for folding a margin of body material back upon itself and for inturning the edge of 20

5 said margin to thereby form a hem-fold, guides disposed at opposite sides of said presser-foot and relatively arranged to narrow to a predetermined width the hem-fold delivered by said folder, supporting means for the inner fold-edge guide providing for yielding movements thereof relatively to said work-support, and means for reciprocating said presser-foot relatively to said guides to engage and release the work during 10 each stitch-forming cycle.

6. In a sewing machine, a work-support, stitch-forming mechanism including a reciprocatory needle work-feeding means, a presser-foot, a folder disposed in front of said presser-foot having means for folding a margin of body material 15 back upon itself to form the outer fold of a hem, and for inturning the edge of the folded back margin to thereby form the inner fold of the hem, a hem-shaping member disposed adjacent said presser-foot having a guiding face for the 20 inner fold-edge of the hem terminating in a fin extending underneath said presser-foot, a fixed pivotal-support for said hem-shaping member, means yieldingly urging said member toward said work-support, and means for guiding the 25 outer fold-edge of the hem delivered by said folder.

JAMES E. ACKERMAN.
